III

ABSTRACT OF THE DISCLOSURE

The inventive method comprises administering a safe and effective amount of a selected morphanthridine derivative to an animal, especially a human being, afflicted with Parkinson's disease or a drug-induced extrapyramidal disorder to control the symptoms of the disease. Specific morphanthridine derivatives disclosed are 5-methyl-11-(3-piperidino)propyl-5,6-dihydromorphanthridine, 5-benzyl-11-[4-(N-methylpiperidylene)]-5,6-dihydromorphanthridine and 5-methyl-11-(3-dimethylamino)propylidene-5,6-dihydromorphanthridine.

10

15 in which X and X_1 are selected from hydrogen, a halogen such as chloro or bromo, a lower alkoxy such as methoxy or ethoxy, a lower alkyl thio such as thiomethyl or thioethyl and trifluoromethyl, R_1 is hydrogen, a lower alkyl of 1 to 4 carbon atoms or a phenyl-lower alkyl of 7 to 13 carbon atoms such as benzyl, phenethyl, phenylisopropyl, and the like, A is a straight or branched chain lower alkylene of 2 to 6 carbon atoms, and R_2 and R_3 are selected from hydrogen, a lower alkyl of 1 to 4 carbon atoms and phenyl-lower alkyl of 7 to 10 carbon atoms or

BACKGROUND OF THE INVENTION

In both Parkinson's disease and drug-induced extrapyramidal disorders, the patient exhibits one or more of the following symptoms: tremor, rigidity, increased salivation, akathisia, manifested by extreme restlessness, and dyskinesias, characterized by spastic contractions and involuntary movements.

25

The drug most widely prescribed for use in the treatment of Parkinson's disease and the drug-induced extra-pyramidal disorders is 3-(1-pyridyl)-1-phenylcyclohexyl-1-propanol hydrochloride. Unfortunately, this agent and the other currently available agents for treatment of Parkinson's disease possess side effects which limit their use. In addition, many of the patients afflicted with Parkinson's disease are refractory and do not respond favorably to treatment with any of the presently available agents so that, obviously, additional agents such as those of the present invention are needed. 35 40

The compounds employed in the novel method of the present invention are known compounds or homologs of known compounds (see U.S. Patent Nos. 3,267,094 and 3,153,652).

SUMMARY OF THE INVENTION

In the practice of the invention, an animal, especially a person afflicted with Parkinson's disease or a drug-induced extrapyramidal disorder, is administered a safe and effective amount of a compound or a nontoxic salt of a compound selected from compounds of the formulae:

5

50 it is usually preferred to employ them in the form of a pharmaceutically acceptable salt. Representative of the acid addition salts which may be employed are the hydrochloride, sulfate, phosphate, acetate, fumarate succinate, maleate, sulfamate, and dicyclohexylsulfamate.

55 Among the compounds of Formula I which may be employed in the method of the invention are the following:

5-methyl-11-(3-dimethylamino)propylidene-5,6-dihydromorphanthridine,
 60 5-methyl-11-(3-dimethylamino-2-methylpropylidene)-5,6-dihydromorphanthridine,
 5-methyl-11-(3-methylamino)propylidene-5,6-dihydromorphanthridine,
 65 3-chloro-5-methyl-11-(3-dimethylamino)propylidene-5,6-dihydromorphanthridine, and
 5-methyl-11-[3-(4-methylpiperazino)-propylidene]-5,6-dihydromorphanthridine.

95

Each of the above compounds, when administered to mice in doses of 20 mg./kg. intraperitoneally, prior to challenge with either tremorine or oxotremorine, blocked the tremors normally induced when tremorine or oxotremorine are administered to nonpretreated mice intraperitoneally. This is considered a significant indication of anti-Parkinsonism activity, for both tremorine and oxotremorine induce a Parkinson disease-like behavior characterized by tremor, rigidity and parasympathomimetic stimulation in mice, rats, rabbits, dogs and monkeys. The similarity of tremorine and oxotremorine-induced behavior in animals to that seen in Parkinson's disease in man, and the fact that all agents found to be useful in treating Parkinson's disease also block the effects of tremorine and oxotremorine in animals, has led to the general use of tremorine and oxotremorine in the screening of drugs for anti-Parkinsonism activity (Everett, et al., *Science*, 124, 79 (1956) and Cho, et al. *Biochem. biophys. Res. Commun.* 5, 276 (1961)).

Compounds of Formula II which may be employed in the method of the invention are the following:

5-benzyl-11-[4-(N-methyl-4-piperidylene)]-5,6-dihydromorphanthidine, and

5-methyl-11-(N-methyl-4-piperidylene)-5,6-dihydromorphanthidine.

Each of the above compounds blocked tremorine-induced tremors when administered to mice prior to challenge in doses of less than 10 mg./kg. intraperitoneally.

Compounds of Formula III which may be employed in the method of the invention are the following:

5-methyl-11-(3-piperidino)propyl-5,6-dihydromorphanthidine,

5-methyl-11-[3-(N'-methyl)piperazine]propyl-5,6-dihydromorphanthidine,

5-methyl-11-(3-methylamino)propyl-5,6-dihydromorphanthidine,

5-methyl-11-(1-dimethylamino-3-butyl)-5,6-dihydromorphanthidine,

5-chloro-5-methyl-11-(3-N-methyl-N-benzylamino)propyl-5,6-dihydromorphanthidine, and

5-chloro-5-methyl-11-(3-methylamino)propyl-5,6-dihydromorphanthidine.

Each of the above compounds blocked tremorine-induced tremors when administered to mice prior to challenge in doses of less than 20 mg./kg. intraperitoneally.

Representative of suitable pharmaceutical compositions which may be prepared are the following:

TABLETS

5-methyl-11-(3-dimethylamino)propylidene-5,6-dihydromorphanthidine dicyclohexylsulfamate	25
Methyl cellulose, 400 cps.	4
Lactose	9
Magnesium stearate	0.4
Tartr	1.6

The powders, other than magnesium stearate, are granulated with water, passed through a No. 16 mesh screen and dried at 50° C. Magnesium stearate is mixed in and 0 mg. tablets are pressed.

The practice of the invention is further illustrated by the following example:

EXAMPLE

Sixteen human patients suffering from Parkinson's disease were administered tablets containing 2 mg. each of the compound 5-methyl-11-(3-dimethylamino)propylidene-5,6-dihydromorphanthidine. The following is a summary of the results of the study. The patients received doses ranging from 6 mg. per day to 50 mg. per day. All sixteen of the patients had tremor. Eleven of the patients

responded favorably to the medication with reduced tremor. Of the eight patients that had rigidity, in addition to tremor, six improved on the medication. As part of the controlled study, placebos were administered in six cases, however, no placebo response was observed.

The method of the present invention appears to possess a significant advantage over previous treatments of Parkinson's disease in that the beneficial effects of the method are not accompanied by the same degree of undesirable peripheral anticholinergic activity as previous methods.

I claim:

1. A method of controlling the tremor and rigidity of Parkinson's disease or a drug-induced extra-pyramidal disorder in an animal which is afflicted with said disease or disorder which comprises administering to said animal a daily dose of 2 to 100 mg. of a compound of the formulae:

or

45 in which X and X₁ are hydrogen, halogen, lower alkoxy, lower alkyl thio or trifluoromethyl, R₁ is hydrogen, lower alkyl of 1 to 4 carbon atoms or a phenyl-lower alkyl of 7 to 10 carbon atoms, A is an alkylene of 2 to 6 carbon atoms, R₂ and R₃ are hydrogen, lower alkyl of 1 to 4 carbon atoms, a phenyl-lower alkyl of 7 to 10 carbon atoms and when taken with the attached N are morpholino, pyrrolidino, piperidino, piperazino or 4-lower alkyl piperazino.

50 2. The method of claim 1 in which the compound administered is a compound of Formula 1 in which R₁ is methyl, A is ethylene, X and X₁ are hydrogen and R₂ and R₃ are methyl.

3. The method of claim 1 in which the compound administered is one in which X and X₁ are hydrogen or chloro.

60 4. The method of claim 1 in which the animal is a human being.
